UNITED STATES PATENT OFFICE.

GEORGE J. BURNS, OF AYER, MASSACHUSETTS.

CHILD'S WAIST.

SPECIFICATION forming part of Letters Patent No. 608,149, dated July 26, 1898.

Application filed November 16, 1897. Serial No. 658,674. (No model.)

To all whom it may concern:

Be it known that I, GEORGE J. BURNS, of Ayer, in the county of Middlesex and State of Massachusetts, have invented certain new and 5 useful Improvements in Children's Waists, of which the following is a specification.

This invention relates to an improved child's waist; and its principal objects are, first, to produce a garment of such a design 10 and construction as may be manufactured with the minimum waste of material; secondly, to produce a garment of superior fitting qualities; thirdly, to produce a garment which shall possess by reason of its construction a high degree of durability and a high 15 degree of comfort for the wearer.

To these ends the invention consists of the improved garment which I shall now proceed to describe and claim.

20 Of the accompanying drawings, forming part of this specification, Figure 1 is a view representing the outer side of a child's waist constructed according to my invention. Fig. 2 is a view indicating my improved method 25 of cutting the cloth for the body of the garment. Fig. 3 is a similar view showing the old method of cutting. Fig. 4 represents the waist in position on the wearer.

The same reference characters indicate the 30 same parts in all the figures.

Referring to the drawings, *a* designates the body portion or foundation-piece of the garment, consisting, preferably, of a single thickness of cloth and cut after the manner indicated in Fig. 2, which will presently be described.

35 *b b* designate two gores or triangular pieces of cloth inserted under the armholes *c* and sewed along two edges to the main body portion *a*, and *d d* designate the shoulder-straps, which are sewed along their length to the body portion *a*. The armholes *c* and the edges of the garment are bound in the ordinary manner, and the usual facing or strengthening 40 strips *a' a²* are provided for the buttonholes and buttons by means of which the waist is buttoned around the body of the wearer.

45 *e e* designate the buttons by means of which the lower outer garment, such as a skirt or trousers, is attached to the waist, the said buttons being fastened on various strips *f g h*, which are sewed to the garment and form

part thereof. These strips are so arranged that substantially all of the strain of the attached lower garments is borne from the shoulders of the wearer. The strips *f f* start at the middle of the back or the middle of the front of the waist, depending upon whether the garment is to be buttoned in front or behind, and pass over the shoulder-straps *d* to 55 the facing-strips *a'* and *a²*, respectively. The two pairs of strips *g g* start at common points underneath the armholes *c* and pass diagonally upward in V fashion on either side of said armholes, their ends being sewed underneath the strips *f f*.

The strips *g*, besides acting as supporters, serve to cover and reinforce the seams where the gores *b* are sewed to the main body portion *a*.

60 On the back or front and sides of the garment, at the three points where the lower ends of the strips *f f* and the strips *g g* come together, are sewed diamond-shaped pieces of cloth *i i'*, these being the points where the 65 principal weight of the lower garments is supported. These pieces serve to cover the unfinished ends of the strips *f* and *g*, impart a neat appearance to the garment, and afford a strong foundation for attaching buttons *e* 70 and *e*. The lower edges of the side pieces *i* are left free from the body-piece *a* on account of the fullness of the garment at these points. The strips *h* are substantially vertical and 75 extend from the junction of the strips *f* and *g* to the lower edge of the garment, each acting as a support for one of the buttons *e*. These strips may, however, be omitted, as they are used only on waists where support for 80 nether garments is required at these points. 90

An inspection of Fig. 3, which represents the ordinary way of cutting the cloth for the body portion of a waist, and of Fig. 2, which represents my improved method of cutting, will indicate at once the great saving of material incident to the latter method. The greatest waste in cutting garments in the old way occurs in the armhole, since the remnants of cloth therefrom are not of suitable shape or size to be used as any part of the garment. 95 It is ordinarily impossible by this method to get two waists from a piece of twenty-seven-inch goods; but by means of my improved method this is easily accomplished. In the 100

pattern Fig. 2 it is seen that the shoulder-
straps are cut short or incomplete, the miss-
ing portions being supplied from other pieces
of goods, and that the armholes are repre-
5 sented by narrow recesses 6 6 and slits 7 7,
which are afterward spread apart for the in-
sertion of the triangular pieces *b*. These lat-
ter pieces can be cut from the remnants oc-
curring by reason of the angles formed be-
10 tween the end portions 2 of the base-line and
the middle portion 3 thereof.

The recesses 6 and slits 7 may be said to
subdivide the body *a* into a middle section 8
and two end sections 9 9, the upper ends of
15 which are shoulder-strap bases 5 5. When the
gores *b b* are inserted between the edges of
the slits 7 7, they separate the upper portions
of the end sections from the middle section,
thereby depressing the lower edges 2 2 of the
20 end sections and forming full portions 4 4 be-
low the gores, where the garment covers the
wearer's hips. Fig. 1 shows the base-line of
the garment as turning upwardly at the ends;
but when the garment is laid out perfectly
25 flat this base becomes substantially a straight
line.

In order to provide for the larger circum-
ference of the child's body below the waist-
line, it has heretofore been necessary either
30 to lay a box-plait under the arms, leaving it
free below the waist-line, or to cut a gash over
the hips below the waist-line or to make the
waist out of separate pieces of cloth cut for
the seam under the arm at such an angle as
35 will give the required fit, all of which meth-
ods are disadvantageous either on account of
appearance, fit, or expense of manufacture.

It will be seen that my improved garment
combines neatness of appearance and supe-
40 rior fitting qualities with strength, economy
of material, and cheapness of manufacture.

Each of the strips *f*, it will be observed,
passes as a continuous band over the shoul-
der, from the diamond at one end to the but-
45 tonhole-strip or button-strip at the other, and
therefore directly takes the strain of the
lower clothing. In garments of this kind as
heretofore constructed the shoulder-strap
has usually been the weakest part. Increased
50 strength is given by this continuous strip, and

the absence of unnecessary seams gives added
comfort. It will further be observed that
the particular manner in which the strips *f*
and *g* are arranged tends to equalize the strain
from the lower clothing. Supposing equal 55
weights or strains to be imposed upon the
garment at the three diamonds and at the
button and buttonhole-reinforcing strips, the
resultant strain will be downwardly from the
points of junction of the strips *f* and *g* and 60
in a direction at right angles to the base-line—
that is, the pull will be directly downward
from the shoulders and not a lateral pull, as
would be the case were the weight wholly
upon the strip *f* or the strip *g* alone. 65

I claim—

1. The herein-described waist, the same
comprising the body portion having shoulder-
strap bases 5 each side of each armhole and
terminating short of each other above the 70
armhole, gore-pieces secured to the body por-
tion under the armholes, and reinforcing-
strips extending down each side of the arm-
hole and extending across the space between
the ends of the shoulder-strap bases 5 and con- 75
necting said bases.

2. The herein-described waist, the same
comprising a main foundation-piece, the
lower edge of which is continuous and longer
than the waist-encircling portion and having 80
a shoulder extension arising from each side,
the under-arm pieces being gores secured to
the body portion and having reinforcing-
strips stitched to the shoulder extensions and
forming the upper sides of the armholes, the 85
said reinforcing-strips constituting a part of
the garment, supporting-strips arranged in
lines extending from the shoulder-covering
portions of the garment, and pieces arranged
at the sides and back or front of the garment 90
and covering the ends of certain of said strips.

In testimony whereof I have signed my
name to this specification, in the presence of
two subscribing witnesses, this 12th day of
November, A. D. 1897.

GEORGE J. BURNS.
